UNITED STATES PATENT OFFICE.

WALLACE H. JENKINS, JAMES GRIST, AND JOHN GRIST, OF PHILADELPHIA, PENNSYLVANIA.

DESIGN FOR EDGING.

SPECIFICATION forming part of Design No. 21,276, dated January 5, 1892.

Application filed December 2, 1891. Serial No. 413,836. Term of patent 7 years.

To all whom it may concern:

Be it known that we, WALLACE H. JENKINS, JAMES GRIST, and JOHN GRIST, citizens of the United States, residing at Philadelphia, 5 in the county of Philadelphia and State of Pennsylvania, have invented and produced a new and original Design for Edging; and we do declare the following to be a full, clear, and exact description of the same, reference being had to the accompanying drawing, forming a part thereof.

The leading features of our design consist in an edging having the parallel plaits $a a'$ connected by open-work, as shown. This part 15 is intermeshed with corresponding parallel plaits, and at the lower edge of the edging is an ornamentation representing shells, as shown in the drawing.

Letters of reference are used to indicate the 20 different parts of the design in the drawing. A indicates an edging having the parallel

plaits $a a'$ connected by open-work e . This part of the edging is connected with corresponding parallel plaits $d d'$ by cross-cords $f f$, and d and d' are connected by a running 25 loop g . At suitable intervals between the plaits $d d'$ are worked the bases c of closed bivalvular shells B , whose outer edges overlap the plait d' and loop g and form the scalloped border i of the edging. 30

What we claim, and desire to secure, is—
The design for edging, as herein shown and described.

In testimony whereof we affix our signatures in presence of two witnesses.

WALLACE H. JENKINS.
JAMES GRIST.
JOHN GRIST.
